COMBINED SMOKING PIPE RACK AND COVER THEREFOR

Bernard Hochstein, New York, N. Y.

Application May 10, 1957, Serial No. 46,110

Term of patent 7 years

(Cl. D85—2)

Fig. 1 is a perspective view of a combined smoking pipe rack and cover therefor, showing my new design;

Fig. 2 is an exploded, front elevational view of the same;

Fig. 3 is an end elevational view of the same;

Fig. 4 is an elevational view of the other end thereof; and

Fig. 5 is a top plan view of the same.

I claim:

The ornamental design for a combined smoking pipe rack and cover therefor, substantially as shown.
